UNITED STATES PATENT OFFICE

ANDREW LOVE, OF PADDINGTON, NEW SOUTH WALES, AUSTRALIA

SHOE FASTENING

Application filed December 1, 1928, Serial No. 322,979, and in Australia January 3, 1928.

There have been devised many substitutes for the ordinary laces by which shoes are usually adjusted and secured on the feet of the wearer, and the object of this invention is to provide a fastener which can be rapidly 5 and easily adjusted and released, which is sufficiently elastic to allow for the expansion of the foot and thus avoid uncomfortable pressure on the instep, and which, when in use, presents a marked resemblance to ordinary lacing while avoiding the disadvantages thereof.

Fastening means according to this invention comprise a pair of light stiff rods loosely hinged together at one end, one of them having 15 near its other end a catch to releasably engage the other rod, and both of them being terminally formed at the ends remote from the hinge to provide finger grips whereby they are manipulated as hereinafter described, and, in association with said rods, a plurality of loops of rubber for engagement thereby and for threading through and anchoring in the shoe eyelets as hereinafter described.

25 When the fastener is applied to a shoe, the rubber loops project through the eyelets on either side of the shoe opening being anchored on the inside thereof, one of the rods being threaded through the loops on each side 30 of the opening. To draw the edges of the opening together and fasten the shoe, the finger grips are grasped between the thumb and the finger and the rods drawn together thus stretching the loops, while at the same 35 time the catch-carrying rod is slightly rotated to enable its catch to pass under and engage the other. To release or unfasten the shoe, the catch-carrying rod is slightly rotated to free the catch and the finger grips 40 are then released so that under the tension of the loops the rods spring apart.

To more fully and clearly describe the invention and its application to a shoe, reference is now made to the accompanying drawings (all perspective) which depict a fastener

according to this invention and in which—

Fig. 1 shows the fastener applied to a shoe and with the parts closed and fastened.

Fig. 2 showing the shoe with the parts unfastened.

Fig. 3 is a fragmentary view showing portion of the inside of one side of the shoe front and the preferred means of anchoring the loops.

Fig. 4 shows the two rods complete;

Fig. 5 is a fragmentary view showing two 55 rings in position on opposite sides of the shoe opening;

Fig. 6 is a fragmentary view showing a modification of the method of anchoring the rings, a single ring serving two adjacent eyelets.

Referring to Figs. 1 to 5 inclusive, rubber loops A.A are threaded through the eyelets B.B of the shoe on each side of the opening and are secured on the inside by a flexible anchor bar C (Fig. 3) threaded through them, said bar being formed at its ends with palms D.D to prevent its longitudinal displacement. This anchor bar consists of a comparatively thin strip, so as to lie flat against the inside 65 of the shoe front, and is preferably of rubber to avoid a hard excrescence on the inside of the shoe.

Through the outwardly projecting portions of the loops A.A on one side of the shoe-opening is threaded the rod E and through those on the other side, the rod F. These rods are clearly shown in Fig. 4, and are formed respectively at one end to constitute the elements of a hook-and-eye hinge G. This constitutes a loose connection of which the elements are preferably separable to facilitate the threading of the rods through the loops. At its other end the rod E is bent or shaped 80 to form a finger grip H, the extreme end being upturned to form a catch J. The corresponding end of rod F is also bent or shaped to form a finger grip K. These parts are so formed that as the finger grips are moved to 85 90

wards each other with a slight lifting of grip K and a slight turning of grip H (and rod E) to depress catch J, the latter will pass under rod F so that when the grips are released the catch engages rod F as shown (in Fig 1,) 5 the parts being retained in this position by the tension of the loops. To release the parts, the grip H is manipulated to again depress catch J against the natural resilience of the 10 foot of the wearer, to release it from rod F, whereupon the rods spring apart and the shoe 15 is unfastened. It will be noted that the catch J is on that side of rod E which is nearer to rod F and that its heel bears upon the surface of the shoe upper, so that the normal tension or pull exerted by the rubber loops does not result in depressing the catch and releasing it from its engagement with rod F; to do this it is necessary to apply lifting pressure 20 to that end of grip H on the side of the rod E remote from the rod F.

Referring to Fig. 6, one rubber loop A¹ is shown threaded through two adjacent eyelets, that portion A² of the loop extending, on the 25 inside of the shoe, between said eyelets constituting the anchoring means.

When a shoe has been secured on the foot of the wearer by the means herein described, the elasticity of the rubber rings, allows a 30 considerable expansion of the shoe-front during walking, running or dancing, thus materially adding to the comfort of the wearer.

What I claim and desire to secure by Letters Patent is:—

35 1. Shoe fastening means, comprising a pair of metal rods hinged together at one end and equipped with means for mutually and releasably engaging their other ends, and a plurality of elastic members for connecting one 40 of said rods to eyelets in one side of a shoe front, and the other rod to eyelets in the other side of a shoe front.

45 2. Shoe fastening means, comprising a pair of metal rods hinged together at one end and equipped with means for mutually and releasably engaging their other ends, and a plurality of rubber loops for connecting one 50 of said rods to eyelets in one side of a shoe front, and the other rod to eyelets in the other side of a shoe front.

55 3. Shoe fastening means according to claim 1, including means for anchoring the elastic members respectively in the eyelets of a shoe front.

4. Shoe fastening means according to claim 1, in which one rod, at the end remote from the hinge, carries a catch member to releasably engage the other rod.

60 5. Shoe fastening means according to claim 1, further characterized in that each rod at the end remote from the hinge is formed to constitute a finger grip for facilitating manipulation.

65 6. Shoe fastening means, comprising a pair of metal rods loosely hinged together at one

end, so that one may be partially rotated in relation to the other, both of said rods being terminally formed at the ends remote from the hinge to constitute finger grips and one of said rods having near its last mentioned end an offset catch to engage the other rod, a set of rubber loops to engage one of said rods and another set to engage the other rod, and means for anchoring the sets of loops respectively in eyelets in the sides of a shoe front.

Signed at Sydney, Australia, this 20th day of July, A. D. 1928.

ANDREW LOVE.
